UNITED STATES PATENT OFFICE.

JOHN WICKS, OF OAK PARK, ILLINOIS, ASSIGNOR TO RESERVE HOLDING COMPANY, OF KANSAS CITY, MISSOURI, A CORPORATION OF DELAWARE.

SWITCHING MECHANISM.

Application filed April 30, 1927. Serial No. 188,031.

The invention relates, broadly stated, to switching apparatus employed in automatic telephone exchanges. More particularly, the invention is concerned with a novel switching mechanism for selecting trunk lines when used as a "selector" or for selecting subscriber's lines when used as a "connector."

The principles involved, and the operations of automatic switches used in automatic telephone exchanges are well known and shall not be explained in this specification. Such apparatus are disclosed for example in the patents to Keith, Erickson & Erickson, #815,176 and #815,371, both granted March 13, 1906. The switches disclosed in these patents are controlled by impulses generated at a calling device at the subscriber's station. The term "selector" is used to designate a switch which responds to a digit in the called subscriber's directory number and then rotates automatically to select a trunk line in the group designated by the digit dialed. The term "connector" is employed to designate a switch which has direct access to called subscriber's line terminals. The connector therefore is responsive to the two last digits dialed by a calling subscriber.

Although the switches described in the patents listed above have no immediate bearing upon the present invention, it will greatly assist the understanding of the description if the known is broadly recalled. A brief account of the salient features and operations of the switches and described in the above patents shall therefore be given.

The essential mechanism consists of a longitudinally and radially movable shaft provided with wipers adapted to engage terminals arranged in groups in horizontal semi-circular rows or levels.

The switch as a whole involves suitable electro-magnetically actuated mechanism for stepping the shaft vertically upwards, thereby positioning the wipers opposite a certain row of terminals containing the desired trunk or line, whereupon the shaft is moved radially to select the trunk or line within the group. In case of a selector, the vertical movement is controlled by the calling subscriber and the rotary movement takes place automatically. In case of a connector, however, both movements are under the calling subscriber's control.

The release of the switch is accomplished upon the subscribers abandoning the call and replacing their receivers. The release magnet energizes, causing the shaft to rotate back by force of a spiral spring and to drop then vertically into its normal position by force of gravity.

Summarizing the features of the usual vertical and rotary switch, the shaft, or rather to say the wipers describe an angular motion, namely, vertically upwards, horizontally within a certain level, and back again during release along the same path, each movement being controlled by a distinct and separate magnet. The switch is thus provided with three operating magnets, the vertical, the rotary, and the release magnet, each executing solely the corresponding operation of the mechanism.

It will be seen presently that the instant invention represents a complete departure from the usual, that is to say, that entirely different and novel principles have been employed in the design and operation of the mechanism. The most conspicuous features, however, which distinguish the disclosed switch from the old and well known apparatus will now be outlined.

In the usual switch the terminals of trunk lines or subscribers lines are arranged horizontally in groups, one group located above the other. Wipers are therefore moved vertically to select the desired row or level and then horizontally within the selected row or level to engage a certain trunk or line.

Each trunk or line consists, as is well known, of a plurality of conductors, which must be made accessible to as many switches as are necessary to take care of the traffic. The terminals accessible to a switch may be made from sheet metal, or the like, and embedded in insulating material, forming an individual terminal bank for each switch. These terminals are usually multiplied by flexible jumper wires or cables with the corresponding terminals of as many switches as required. It will be understood that this arrangement necessitates relatively expensive terminal banks apart from having other inherent disadvantages which are well known to every one familiar with the subject.

It is one object of the present invention to eliminate the usual terminal bank individual to each switch by providing bare wire

terminals, e. g., bare wires which are suspended between two points, and accessible to the wipers of a plurality of switches. Thus, individual terminal banks, and connections between the banks, are entirely eliminated. The wires may be suspended vertically in groups, one group adjacent to the other, and the switches may be mounted in front or in back of the terminal wires. If connection with a certain trunk is desired, the wipers of the corresponding switch are subjected first to a motion in a certain direction to select the group, and then to movement in a right angle to the first motion to select the trunk or line within the selected group.

The switching mechanism disclosed in the present invention is particularly well adapted for using bare wire terminals of the sort intimated above. It consists of interlocked carriages. More specifically, the wipers are fastened to a carriage which has movement, in a certain direction, and is secured by a locking arrangement to a main carriage which has movement in a direction in right angle to the first movement. Initially, the main carriage is actuated, and, since the wiper carriage is locked to the main carriage, it will be evident that the wipers will be subjected to a first movement to select a certain group of terminals. After the group has been selected, the wiper carriage is unlocked from the main carriage and the main carriage is locked in the attained position. The wiper carriage is then moved in a right angle to the first motion, the wipers brushing over the contacts in the selected group to select an idle trunk line if the switch is used as a selector; or a subscriber's line if the switch is used as a connector.

The carriage actuating apparatus is common for imparting the movement to both carriages. It consists of a drum provided with ratchets. The drum carries a steel ribbon which extends over a roller on the main carriage and is attached to the wiper carriage. An escapement serves to impart movement to the drum for unwinding the steel ribbon. If both carriages are locked to each other, movement is possible only in one direction. After unlocking the wiper carriage from the main carriage, the escapement is operated again unwinding the steel ribbon further. The main carriage being locked at this time, a further movement in the same direction is impossible. However, the wiper carriage being unlocked from the main carriage, a further unwinding of the steel ribbon will be effective to the wiper carriage in a direction which is in right angle to the first movement.

The release of the mechanism to normal position takes place upon a call being abandoned by the subscriber. A magnet is operated at that time imparting movement to

the drum in a direction contrary to the setting movement. This will result in winding the steel ribbon upon the drum, thereby withdrawing the wiper carriage, and the wipers, from engagement with the terminals. The wiper carriage, during this movement, locks itself to the main carriage, at the same time unlocking the main carriage from engagement with a locking mechanism. Further operation of the release magnet and corresponding movement of the drum will result in moving the main carriage back to normal position.

The above description which is necessarily incomplete on account of its brevity will be so amplified in the detailed description which is yet to follow. However, it will be seen from the above cursory account that I have employed entirely novel principles resulting in the design of a very simple apparatus which accomplishes the same results as the known device without impairing the reliability of operation. It will be apparent later on that there are a variety of features, objects and advantages apart from those suggested in the foregoing paragraphs. A detailed description of the invention shall now be presented with reference to the drawings comprising Figs. 1-5, inclusive, which form a part of this specification.

Fig. 1 shows a top view of the switch mechanism, the terminals being shown in section in the lower right-hand part of this figure.

Fig. 2 is a side view of the switch shown in Fig. 1. Some of the parts have been omitted in this figure in order to keep the drawing as clear and as simple as possible, and some of the parts have been shown in section.

Fig. 3 is a perspective view of the arrangement of the wipers and of the terminals.

Fig. 4 shows the circuit of a switch as disclosed in the present invention when used as a selector switch.

Fig. 5 shows the circuit of a switch disclosed in the present invention when used as a connector switch.

In Figs. 1 to 3, inclusive, like parts are numbered alike, and I shall, in the course of the following discussion refer to a certain figure only if necessary for a clear understanding.

In Figs. 4 and 5, the usual symbols have been employed for showing the various parts in the conventional manner. A plurality of batteries and ground connections have been shown in these figures. It will be understood of course that this has been done for convenience of description only and that there is in reality only one battery with one pole grounded.

Referring now to the drawings shown in Figs. 1, 2, and 3, it will be seen that the

switch comprises an actuating mechanism consisting of a magnet designated 1, which operates an escapement 4 to impart movement to the drum 5. When this magnet is 5 operated step-by-step by impulses generated at a calling subscribers dial, the steel ribbon 8 will be moved in a direction indicated by the arrow. Whenever the magnet designated 50 is operated, the drum 5 will move 10 in reverse direction moving the steel ribbon 8 accordingly. The magnet 50 is the release magnet of the mechanism and will be operated to actuate the armature 52 and thereby the pawl 53 in a buzzer like manner to impart 15 movement to the drum 5 in an anti-clock-wise direction.

The steel ribbon 8, it will be seen, is fastened to the wiper carriage 10 and is supported on the roller 9 which is fastened to 20 the main carriage 14. The wiper carriage 10 is provided with a projection 11 which terminates in a hook. The shape of the projection and of the hook is best seen in Fig. 2. The main carriage 14 is provided with 25 a bracket 15 to which is pivoted an arm 16. In normal position of the apparatus, the wiper carriage 10 will be locked against movement and will be secured to the main carriage 14 by means of the movable arm 16 30 which catches the hook on projection 11 of the wiper carriage 10. The bracket 15 of the main carriage 14 is at its upper end provided with a movable locking arm 17 which has a projection 17'. This arm 17 is normally resting on the movable arm 16 and thereby prevented from movement which would otherwise take place on account of the spring 41 which is at one end attached to the arm 17 and at the other end to the bracket 15. 35 The main carriage is also provided with four rollers 20, 21, 22 and 23 which adapt it to move along the tracks provided on the mounting plate 24.

It will be apparent from the drawings 45 that the movement of the main carriage is entirely dependent on the movement of the steel ribbon 8. Should the escapement magnet 1 be actuated, the steel ribbon will be unwound and move in the direction of the 50 arrow, thereby permitting the main carriage 14 to move along the tracks on the mounting plate 24. In order to achieve the movement of the main carriage, a spiral spring 43 is provided which is at one end fastened to 55 the movable carriage 14 and at the other end may be fastened to a convenient point on the mounting plate 24.

When the main carriage is initially moved 60 the wiper carriage 10 will participate in the movement thereby moving the wipers, which are fastened to the arm 38, to position them opposite a certain group of terminals. A magnet 26 is provided on the mounting plate 24. This magnet when operated is 65 adapted to tilt the bar 29 which is pivoted

in the brackets 30 and 31. Referring particularly to Fig. 2, it will be seen that the bar 29 when moved by the operation of the magnet 26, will unlock the wiper carriage 10 from the main carriage 14 by moving the 70 arm 16 to the left and liberating thereby the hook which is provided on the projection 11 of the wiper carriage 10. Simultaneously with unlocking the wiper carriage from the main carriage 14, the arm 12 which is movably mounted on the projection 11 of the wiper carriage will be moved to the right against the tension of the spring 42. The upper part of the arm 16 will move to the right under the action of the bar 29. The 75 locking lever 17 mounted pivotally on the bracket 15 will now move under the tension of spring 41 and the upper end of the arm 16 will engage the opening 40 in the locking lever 17. At the same time the projection 17' on the locking lever 17 will engage one of the notches 19 in the locking bar 18. The notch engaged by the projection 17' of the locking lever 17 corresponds of course to the group of bank terminals 80 to which the wipers have been moved.

The escapement magnet 1 is then operated again to unwind the steel ribbon 8 further. A further movement of the main carriage in the same direction is prevented at this 85 time on account of the locking lever 17 engaging the locking bar 18. The wiper carriage 10 is unlocked at this instant from engagement with the main carriage 14. A further actuation of the escapement magnet 100 1 will therefore result in a movement of the wiper carriage 10 along the tracks 32 and 33 which are engaged by the wheels 34, 35, 36 and 37, provided on the wiper carriage. The tracks 32 and 33 it will be seen are 105 fastened to the main carriage 14. The movement of the wiper carriage is achieved by means of the spring 39 which has a tendency to pull the wiper carriage 10 in a right angle away from the main carriage. The 110 extent to which the pull of the spring 39 can be effective is, it will be obvious, dependent on the extent of un-winding the steel ribbon 8. The wiper carriage moves thus the arm 38 which at its lower end carries the wipers 44, 45 and 46. These wipers brush over the terminal group selected by the first movement. The selection of terminals will be described in connection with the explanation of the circuits shown in 115 120 Figs. 4 and 5.

Returning to the description of the movement of the wiper carriage 10, it will be recalled that when magnet 26 was operated 125 the bar 29 was tilted to unlock the wiper carriage from engagement with the main carriage. At the same time the lever 12 was moved against the tension of spring 42. The magnet 26, after having accomplished the unlocking of the wiper carriage from 130

the main carriage, returns to normal position. This occurs during the movement of the wiper carriage. The lever 12 will therefore return to the position shown in Fig. 2. The purpose of the lever 12 is to restore the locking condition between the main carriage 14 and the wiper carriage 10 to accomplish the release to normal position.

To effect the release, the magnet 50 is energized and deenergized in rapid succession, thereby operating the armature 52 and the pawl 53. The drum 5 is thereby moved in a direction contrary to the setting movement. This results first in withdrawing the wiper carriage 10, and thereby the wipers, from engagement with the terminals. In the course of its release motion, the wiper carriage will attain the position in which it is shown in Fig. 2. Shortly before this occurs, the arm 12 will strike the locking lever 17 and lift the same against the tension of the spring 41. This amounts of course to an unlocking of the main carriage 14 by releasing the main carriage from engagement with the locking bar 18 and permitting the locking arm 16 to engage the hook provided on the projection 11 of the wiper carriage. A further movement is therefore prevented. However, both carriages will now move back to normal position. An off-normal contact is shown at 56 mounted on a bracket 57 which in turn is secured to the mounting plate 24. The main carriage operates this off-normal contact and thereby interrupts the circuit of the release magnet 50. The mechanism has now returned to normal position as shown in the drawing and is ready to be used for another call. The operation of the mechanism will be more clearly understood from the description of the circuits shown in Figs. 4 and 5.

The arrangement of the terminals accessible to the switching mechanism explained in the foregoing paragraphs shall now be discussed somewhat more in detail.

The terminals shown in the right hand lower corner of Fig. 1 are shown in cross-section. In Fig. 3, a part of these terminals and the wipers of the switch are shown in perspective. These terminals consist of bare wires suspended vertically (or horizontally) between two convenient points. The switches are located with respect to the terminals, as is shown in Fig. 1. Intermediate supports may be provided to prevent vibration of the terminal wires. In the drawings, the wires have been shown to be of rectangular cross-section. However, it will be understood that circular wires may be used as well.

One set of contacts belonging to a trunk or to a line, comprises three terminal wires. One of the sets of contacts has been designated with 47, 48 and 49. A plurality of such sets of contacts are arranged in a row

and these rows are located adjacent to each other. Two contacts, for example 47 and 48, or 47 and 49, may be the line contacts. One contact, which may be either contact 48 or contact 49 in accordance with what arrangement is chosen, may be the terminal representing the release trunk. If the contacts 47 and 49 are line contacts, for example, the corresponding release contact will be contact 48. If, on the other hand, the contacts 47 and 48 are the line contacts, the corresponding release terminal will be 49. It will be readily seen from Fig. 3, that the contacts may be accessible to a number of switches depending on the height or length of the suspended terminal wires and it will also be seen from this figure, how the wipers of a switch, which are designated 44, 45 and 46, gain access to the terminals within the rows.

The operation of the switch mechanism will now be explained with reference to the circuits shown in Figs. 4 and 5. Fig. 4 represents a "selector", and receives one series of impulses generated at a calling subscriber's substation which series corresponds to a certain digit in the called subscriber's directory number. In response to the impulses the wipers will be moved and will thereby be positioned opposite a certain row of contacts. The mechanism is then operated automatically to move the wipers in a right angle to the first movement to cause thereby the selection of an idle set of terminals within the selected row. The operation of the switch shown in Fig. 4 is as follows:

The switch may be accessible to a preceding selector switch or it may be accessible to a subscriber's lineswitch. When the switch is selected, a circuit will be closed for the operation of the line relay 5 which energizes over the calling subscriber's line loop by way of the line conductors 2 and 4. Relay 5 operates its armature 6 closing thereby a circuit for the release relay 10. This relay is normally short circuited over the normally closed contacts controlled by armature 6 to battery over resistance 8. At its armature 11 the relay 10 completes a circuit for the energization of the relay 15 from ground, closed off-normal springs 9, armature 11 and its make contact, resistance 28, lower winding of relay 15, armature 21 and its resting contact, normally closed contacts controlled by armature 48, winding of relay 25, and winding of the motor magnet 30, to battery. The motor magnet 30 and the relay 25 do not operate in this circuit on account of the high resistance of the lower winding of relay 15 and the resistance 28. At armature 12 the relay 10 connects ground to the release trunk in order to hold the preceding switch or switches in operated position; at armature 13 a circuit is prepared for the testing and switching relay 45; at armature 14 a holding circuit is prepared for the upper winding of

relay 15; and at armature 22, the relay 10 disconnects the release magnet 40, at the same time preparing a circuit for the switching magnet 35.

- 5 When relay 15 operates it switches its armature 16 into alternate position, thereby disconnecting the line conductor 2 from the operating circuits and connecting ground from the normally-closed contacts controlled 10 by armature 46; to the armature 11 of relay 10. Armature 11 is now grounded from the off-normal springs 9 and from the normally closed contacts controlled by armature 46. The latter ground connection replaces the 15 former during the stepping movement after the off-normal springs 9 have been opened. At armature 17, the relay 15 connects its upper winding to the now closed contact of armature 14. The upper winding of relay 20 20 15 is at the present time short circuited from armature 6 of relay 15. This of course renders the relay 15 slow-acting. At armature 18, the relay opens a point in the energizing circuit of relay 20. The latter relay 25 serves the purpose of feeding talking current to a called subscriber and its operation will be described presently. At armature 19, relay 15 separates the incoming line conductor 4 from the operating circuits. 30 It will be well to remember that the magnet 30 shown in this drawing corresponds to the motor magnet 1 shown in Fig. 1, while the magnet 35 corresponds to the switching magnet 26 shown in Fig. 1. The 35 switch is now in readiness to receive the impulses generated at the subscriber's station.

The operation of the calling device at the subscriber's station results in the transmission of impulses to the line relay 5, whose circuit will be interrupted a plurality of times in rapid succession. The impulses delivered to the line relay 5 correspond to the digit dialed by the calling subscriber. The 40 motor magnet 30, which corresponds to the motor magnet 1 in Fig. 1, will now be operated in accordance with the dialed impulses and will actuate the escapement 4 in Fig. 1, allowing the drum 5 to unwind the steel rope 8. The unwinding of the steel rope 8 permits the spring 43 to exercise a pulling action on the carriage 14 moving the carriage along its tracks. Since the wiper carriage 10 is locked to the main carriage, the wipers will follow this movement and will be positioned opposite a certain row of terminals. The actuation of the motor magnet 30 in response to the impulses transmitted to the line relay 5, takes place as follows.

It will be recalled that the motor magnet 30 and the slow-acting series relay 25 were connected in series with the lower winding of relay 15 and the resistance 28 to ground on off-normal springs 9. The relay 15 was

energized, while the motor magnet 30 and the slow-acting relay 25 were prevented from operating on account of the high resistance of the lower winding of relay 15 and of the resistance 28. When the line relay 5 deenergizes for the first time, in response to the transmission of the first impulse, its armatures move to normal position in which they are shown in the drawing. This results in the elimination of the lower winding of relay 15 in series with the resistance 28. A direct ground impulse is now transmitted to the motor magnet 30 in series with the slow-acting relay 25. This circuit may be traced from ground, off-normal contacts 9, armature 11 and its make contact, resting contact and armature 7, normal contact controlled by armature 48, winding of relay 25, winding of the motor magnet 30, to battery. The relay 25 energizes in series with the motor magnet 30 and opens at its armature 26 a point in the circuit of the switching magnet 35. Relay 25 is slow-acting and remains energized throughout the transmission of impulses to the motor magnet 30. Relay 15 which was rendered slow-acting prior to the transmission of the first impulse, due to the short circuit around its upper winding, does not release in spite of the fact that its lower winding is being short-circuited at the contacts on armature 7. Whenever the line relay 5 deenergizes a circuit is closed for the upper winding of relay 15 to secure the energization of this relay. This latter circuit extends over the resistance 8 and the normally closed contacts controlled by armature 6. Relay 10 which was originally energized upon the operation of line relay 5 does not release during the transmission of impulses but remains operated in series with the upper winding of relay 15. Therefore, during the transmission of impulses, the relays 10, 15 and 25 will stay operated.

All off-normal springs will be switched when the main carriage designated 14, in Fig. 1, moves out of its normal position. Springs 9 open and disconnect ground from the armature 11 of relay 10. However, this armature still remains grounded from the normally closed contacts controlled by armature 46. Off-normal springs 27 and 29 close to prepare circuits which are at the present time of no consequence and shall be described later. The second and the following impulses belonging to the digit delivered to the line relay 5 are transmitted to the motor magnet 30 over the same path as the first impulse with the exception that ground is supplied from the normally closed contacts controlled by armature 46 by way of armature 16 and its make contact.

Upon the termination of the transmission of the digit, the wipers must be moved within the selected row of bank contacts to

- make engagement with an idle set of bank contacts or, in other words, to select an idle trunk line. The next operation necessary is, therefore, to unlock the wiper carriage 10 from engagement with the main carriage 14 and to lock the main carriage against further movement. This it will be remembered is done by operating the magnet 26 shown in Fig. 1 and thereby tilting the bar 29.
- 10 The magnet 35 in Fig. 4 corresponds to the magnet 26 in Fig. 1. This magnet must energize now. Upon the termination of the digit the series relay 25 deenergizes and closes its armature 26 thereby completing the circuit for magnet 35 from battery, winding of magnet 35, armature 26 and its resting contact, make contact and armature 22, resting contact and armature 47, closed off-normal springs 29, to ground. The wiper carriage 10 is now unlocked from engagement with the main carriage 14, while the latter is locked in engagement with the locking bar designated 18 in Fig. 1. A further set of impulses must be delivered now to the motor magnet 30, or rather to say, the motor magnet 30 must be operated intermittently in order to unwind the steel rope 8 further to permit the wiper carriage 10 to move for the purpose of hunting for an idle trunk line within the selected row. This is done as follows.
- 15 When the switching magnet 35 operates, it closes its armature 36, thereby connecting the motor magnet 30 in parallel to its own winding. The motor magnet 30 therefore receives an impulse and actuates the escapement 4 in the usual manner to permit the further unwinding of the steel rope 8 from the drum 5. The wipers 32, 34 and 23 are now in engagement with the first set of bank contacts in the corresponding row. The further operation of the switch depends on the busy or idle condition of the trunk with which the wipers have made engagement.
- 20 If the selected trunk is busy, the motor magnet 30 must receive another impulse to permit further movement of the wiper carriage. If the selected trunk is idle, however, the circuit of the motor magnet must be opened and the switch must be locked in the position with the wipers engaging the selected trunk. It will be seen that the wiper 34, which is the test or private wiper of the switch is at the present time connected to the upper winding of relay 45 by way of armature 13 and its make contact. The upper winding of relay 45 is connected in series with the lower winding to ground. The testing method adopted in the present case consists in changing the potential on the release trunk. To explain this a little further, it may be pointed out that the test relay 45 has a high resistance winding and a low resistance winding. During testing, both windings are connected in series, and the relay requires for its energization a certain potential on the release conductor of the selected trunk. This potential is present if the selected trunk is idle. In case the selected trunk is busy, that is, in case another switch such as the one shown in Fig. 4 has already selected the trunk, the switching relay of that switch, corresponding to the relay 45, will be in energized position, and will have eliminated its high resistance winding, thereby changing the potential on the test terminal of the trunk. Now, if the test and switching relay 45 of the present switch should engage a test terminal which is connected to ground over a low resistance of another test relay such as 45 of another switch such as shown in Fig. 4, it is evident that the test relay 45 is prevented from operating on account of being short circuited to ground on the busy test terminal. Thus, the energization of the test relay on a busy trunk is prevented.
- 25 A trunk is idle if its test terminal such for example as terminal 29 is connected to battery in the succeeding switch over the winding of a certain relay, such for instance as relay 50 in Fig. 5. If such condition exists, the relay 45 will energize from battery on the test terminal, wiper 34, armature 13 and its make contact, and its low resistance winding in series with its high resistance winding to ground.
- 30 It shall be assumed first that the trunk line, encountered with the first step of the wiper carriage, is busy. The test and switching relay 45 is therefore shunted to ground on the test terminal and cannot operate. The motor magnet 30 upon energizing actuates the armature 31 interrupting thereby its own circuit which extends to ground on the off-normal springs 29. In deenergizing, the motor magnet 30 closes the armature 31 again, thereby completing its own circuit. The magnet 30 receives therefore another impulse and unwinds the steel rope 8 by a further step. Thus the wipers are positioned on the next set of bank contacts. Should this set be busy, a further impulse is delivered to the motor magnet 30 in the same manner as explained and the steel rope 8 is unwound further. This action continues until an idle trunk is found.
- 35 Assuming that the idle trunk is the one having the terminals 37, 39 and 38, the relay 45 will operate and move its armature 47 into alternate position, thereby disconnecting the switching magnet 35 and the motor magnet 30 to prevent further movement of the wipers. It will be seen that when the armature 47 is in alternate position, the high resistance winding of the testing and switching relay 45 is short circuited, and that direct ground is connected to the low resistance winding of relay 45. The short circuiting of the high resistance winding

- changes the potential on the private terminal of the selected trunk line, preventing the switching relay of another switch from operating on this trunk line. At armatures 46 and 48, the relay 45 switches the talking conductors through to the succeeding switch. The series relay 25 and the motor magnet 30 are thereby disconnected at armature 48.
- 10 The lower winding of relay 15 is now bridged across the talking conductors of the succeeding switch as follows: Terminal 37, wiper 32, armature 46 and its make contact, armature 16 and its make contact, armature 11 and its make contact, resistance 28, lower winding of relay 15, armature 21 and its resting contact, make contact and armature 48, wiper 33, terminal 38. If it is assumed that the trunk line connected with leads to a connector such as the one shown in Fig. 5, it will be seen, that the lower winding of relay 15 is now connected to battery and ground over a circuit including the upper talking conductor 57 of the connector, and the armatures 81 and 71, winding of the slow acting relay 60, to the motor magnet 66 and to battery. The motor magnet 66 of course corresponds to the motor magnet 1 in Fig. 1 since it is assumed that the connector illustrated in Fig. 5 is of the structure shown in Fig. 1. The other side of the connection extends over armatures 86 and 73 to ground. The relay 15 of the selector therefore remains in operated position.
- 15 When the connector Fig. 5 is seized in the manner described in the foregoing paragraphs, a circuit is closed for the energizing winding of the holding relay 50. This relay energizes in series with the testing and switching relay 45 of the selector, by way of test terminal 39, release trunk 58, closed off-normal springs 54, lower winding of relay 50, to battery. Upon operating, the relay 50 connects itself in a holding circuit including its upper winding and its armature 51. The switching relay 45 short circuits its high resistance winding to guard the connector against seizure from another hunting selector. At armature 52, the relay 50 disconnects the release magnet 64 and connects ground to conductor 99, thereby preparing various circuits which will be explained later. The motor magnet 66 is normally connected to the upper talking conductor 57 in series with the slow acting relay 60 and the armatures 71 and 81. The lower talking conductor 59 is normally connected to ground over armatures 86 and 73. The preceding selector has connected the relay 15 across the talking conductors. A circuit is therefore closed including the winding of the motor magnet 66, winding of relay 60, and lower winding of relay 15 in the selector. The relay 15 is in this manner kept energized while the relay 60 and the motor magnet 66 of the connector cannot energize on account of the high resistance of relay 15. The connector is now prepared for receiving the first series of impulses.
- 20 When the calling subscriber operates his dialling device, the loop circuit including the line relay 5 of the selector is interrupted a plurality of times according to the digit dialed. Whenever the relay 5 responds to an interruption of the loop circuit and deenergizes, it moves its armature 7 into the position shown in the drawing, thereby short circuiting the high resistance winding of relay 15 and providing a momentary loop circuit to the connector which includes only the slow-acting relay 60 and the motor magnet 66. The relay 60 and the motor magnet 66 operate now in series. Relay 60 remains operated during the entire transmission of the impulses on account of being slow-acting. The motor magnet 66, however, responds to the impulses intermittently and operates the escapement 4 as was already described, in order to move the main carriage to position the wipers 91, 92 and 93 opposite the level in which the desired subscriber's line terminals are located. In the interval between the units and tens digits relay 60 will deenergize and complete thereby a circuit for the switching magnet 90, which corresponds to the switching magnet 26 shown in Fig. 1. This circuit extends from ground, off-normal springs 56, make contact and armature 53, armature 63, and its resting contact, armature 87, and its resting contact, winding of the switching magnet 90 to battery. The switching magnet performs its functions in the usual manner, unlocking the wiper carriage from the main carriage and locking the main carriage to the locking bar. When the last train of impulses arrives, relay 60 operates again in series with the motor magnet 66 and remains in operated position throughout the transmission of impulses. The motor magnet 66 again operates intermittently, moving the wiper carriage in the usual manner to position the wipers 91, 92 and 93 upon the terminals of the wanted subscriber's line. The further operation of the switch depends on the busy or idle condition of the called line.
- 25 If the desired line is busy, there will be ground potential on the private terminal 95. The private wiper 92 is now in connection with the private terminal and when the connection from the private wiper 92 is followed, it will be seen that the busy relay 70 is connected to this wiper over the armatures 83 and 62. If the line is busy the relay 70 energizes in the above circuit and connects busy tone to the upper line conductor at its armature 74. At its armature 72 the busy relay provides a locking circuit for itself which is effective after the

deenergization of relay 60 upon the termination of the impulse transmission. The locking circuit extends from ground, armature 52 and its make contact, armature 72 and its make contact, resting contact controlled by armature 62, winding of relay 70, to battery by way of armature 83 of the switching relay 80. At armatures 71 and 73, the busy relay 70 disconnects the loop circuit extending back to the preceding selector in order to prevent operation of the motor magnet in case the subscriber should attempt to manipulate his calling device for a further digit. When the subscriber responds to the busy signal and replaces his receiver, release will take place in a manner which shall be described presently. If the desired subscriber's line is idle, there will be no ground potential on the private terminal 95. Relay 70 will therefore remain in normal position. Relay 60 deenergizes shortly after the termination of the impulse transmission and moves the armature 62 in the position shown in the drawing. When this occurs, a circuit will be closed for the operation of the switching relay 80, from ground, armature 52 of relay 50, conductor 99, armature 72 and its resting contact, upper winding of the switching relay 80, resting contact and armature 62, wiper 92, terminal 95, to battery by way of the line relay of the called subscriber's lineswitch, which has not been shown in order to avoid unnecessary complication in the drawings. Upon operating, the switching relay 80 locks itself over its lower winding and its armature 84 to grounded armature 52. At armature 83 the switching relay disconnects the busy relay; at armature 88 it connects ground to the private conductor of the called subscriber's line in order to guard the line against seizure from another connector; at armature 81 the impulsing circuit is disconnected and a point in the talking circuit is closed; at armatures 82 and 85 the line is switched through to the ringing circuit; at armature 86 the talking circuit is prepared over the lower line conductor and the circuit of the switching magnet 90 is disconnected.

Ringing current is now transmitted to the called line from an intermittent ringing current source, conductor 79, upper winding of the ring-cut-off relay 75, resting contact and armature 76, armature 82 and its make contact, wiper 91, terminal 94, bell of the called substation, and back over the lower talking conductor to the terminal 96, wiper 93, make contact and armature 85, armature 78 and its resting contact, to ground. Ringing current is applied to the above circuit intermittently as usual. When the called subscriber replies by removing his receiver, the bell is disconnected and a direct current circuit is closed for the en-

ergization of the ring-cut-off relay 75. This relay energizes and disconnects at its armatures 76 and 78 the ringing current, at the same time completing the talking circuit at these armatures. At its armature 77 the ring cut-off relay locks itself to ground at armature 52.

Returning for a moment to the operation of the selector shown in Fig. 4, it will be remembered that the relay 15 was connected across the talking conductors. During the transmission of impulses this relay remained energized in series with the slow-acting relay 60 and the motor magnet 66. When the switching relay 80 in the connector operates, the loop circuit including the relay 15 is opened at armatures 81 and 86. Following the line conductors at this instant of the operation, it will be seen that they terminate in open contacts of armatures 78 and 76 of the ring-cut-off relay 75. Since relay 75 has not been operated yet, the loop circuit for relay 15 is open and this relay deenergizes. It disconnects itself from the loop circuit at its armature 16 and at its armature 18 it bridges the back bridge relay 20 across the talking conductors. The circuit of the back bridge relay 20 is completed upon operation of the ring-cut-off relay 75 and may be traced as follows: Ground, upper winding of relay 20, resting contact and armature 16, make contact and armature 46, wiper 32, terminal 37, talking conductor 59 of the connector, armature 86 and its make contact, make contact and armature 78, armature 85 and its make contact, wiper 93, subscriber's line terminal 97, subscriber's station, and back to the subscriber's line terminal 94, wiper 91, make contact and armature 82, armature 76, and its make contact, make contact and armature 81, talking conductor 57 of the connector, terminal 38, wiper 33, armature 48 and its make contact, armature 7 and its make contact, resting contact and armature 18, lower winding of back bridge relay 20, to battery. The relay 20 supplies talking current to the called subscriber's station. Upon energizing it operates its armature 21 and opens thereby a point in the circuit of the relay 15. The connection between the calling and the called party is now established.

The release of the switches takes place when the subscribers replace their receivers. When the calling party replaces his receiver, the line relay 5 in the selector will deenergize. At its armature 6, the line relay disconnects ground from the relay 10 and closes the normally closed contacts controlled by armature 6 to short circuit the relay 10.

The latter accordingly deenergizes and opens its armature 13. When this occurs, the circuit for the testing and switching relay 45 in series with the holding relay 50 of the connector will be opened and these

two relays deenergize. At armature 12, the relay 10 disconnects ground from the holding conductor 3 but reconnects ground supplied over the off-normal springs 27. Ground remains therefore connected to the release trunk 3 during the release of the switches, for the purpose of guarding the selector against seizure during the release movement. At armature 22, the relay 10 connects the release magnet 40 to the circuit. The circuit for the release magnet will be completed upon the deenergization of the switching relay 45 and may be traced from ground, off-normal springs 29, armature 47 and its resting contact, armature 22 and its resting contact, contact and armature 41, and winding of the release magnet 40 to battery. The release magnet 40 corresponds to the magnet 50 shown in Fig. 1. It receives an impulse over the circuit traced above and operates its armature thereby imparting motion to the drum 5 shown in Fig. 1. The release magnet opens its own energizing circuit by attracting its armature 41, and releases. Immediately upon release its circuit is closed again over armature 41. Thus the release magnet energizes intermittently, moving the drum 5 in anti-clockwise direction. The steel ribbon 8 is wound up on the drum 5. It will be readily understood that this action results in withdrawing the wiper carriage 10 and with it the wipers from engagement with the selected row of terminals. When the wiper carriage 10 is withdrawn to a sufficient degree, the arm 12 will strike the locking lever 17 as was described, unlocking the main carriage from engagement with the locking bar 18. At the same time, the arm 11 of the wiper carriage 10 will engage the locking hook on the arm 16 of the main carriage, thus locking the main carriage to the wiper carriage. Further operation of the release magnet will result in a movement of the main carriage together with the wiper carriage. When the apparatus attains its normal position in which it is shown in the drawing Fig. 1, the off-normal springs designated 29 in Fig. 4 and designated 56 in Fig. 1, will be opened, disconnecting the release magnet and thereby preventing its further operation. The selector therefore has completely returned to normal position. In Fig. 1 there is only shown one off-normal contact 56. It is of course apparent that a plurality of off-normal contacts may be provided. The contact in Fig. 1 is merely shown for illustrative purposes. Accordingly, there are a plurality of off-normal springs operated by the main carriage, when the main carriage returns to normal. One of these off-normal springs is shown at 27 in Fig. 4. This contact opens and disconnects ground from the release trunk 3. Another off-normal contact is shown at 9 in Fig. 4. This contact closes to reconnect ground to armature 11.

The release of the connector shown in Fig. 5 occurs in a similar manner as the release described in connection with the circuit shown in Fig. 4. The release operations commence upon the disconnection of the circuit of the holding relay 50. When this relay returns to normal, it switches its armature 52 to the position shown in the drawing, thereby completing a circuit for the release magnet 64 which circuit includes closed off-normal springs 55 and a normally closed contact 65 controlled by the release magnet. The operations of the release magnet and the corresponding movements of the wiper carriage and of the main carriage to normal position are substantially the same as those described in connection with the selector shown in Fig. 4.

Having described the mechanism and the circuits in detail, I desire it to be understood that I do not want to be limited in the application of the invention to the precise structure shown. The principles involved obviously lend themselves to application in various fields, and modifications may suggest themselves readily to those skilled in the art. I therefore want to be limited in the application of the invention only to the claims which follow.

What is claimed is:

- An automatic switching mechanism having wipers movable successively in a plurality of straight line motions in different planes, terminals accessible to said wipers, a rotatable circular disc member, and means for progressively rotating said member in a continuous clock-wise direction for moving said wipers successively in two different planes to select certain of said terminals.
- An automatic switching mechanism having wipers movable successively in a plurality of straight line motions in different planes, terminals accessible to said wipers, a rotatable circular member, means for rotating said member in a clock-wise direction for moving said wipers successively in two different planes to select certain of said terminals, and means for rotating said member in an anti-clock-wise direction for moving said wipers into normal position.
- An automatic switching mechanism having movable wipers, stationary terminals, a rotatable circular disc member, and means for progressively rotating said member in a continuous clock-wise direction for moving said wipers in a plurality of successive straight line motions to select certain of said terminals.
- An automatic switching mechanism having movable wipers, stationary terminals, a rotatable circular disc member, and means for progressively rotating said mem-

- station, means operated by said member to move said carrier to select a certain one of said rows of terminals, means for locking said carrier against said first movement and 5 for liberating the same for movement in the second direction, means for automatically moving said carrier to select terminals within said selected row, and means for automatically moving said carrier into normal 10 position.
14. In a signalling system, an automatic switching device for extending a connection from a calling station to a called station, bare wire terminals arranged in groups, said device having access to said terminals in common with a plurality of other devices, wipers mounted on a carrier movable in two straight line motions in different planes, means for locking said carrier against the 15 second of said motions, a rotatable circular operating member, means for rotating said member under directive control of a calling station to move said carrier to select a certain one of said rows of terminals, means for locking said carrier against the first 20 of said motions and for liberating the same for said second motion, means for automatically rotating said circular member to move said carrier to select terminals within 25 said selected row, and means for automatically rotating said circular member to move said carrier into normal position.
15. In a signalling system, an automatic switching device for extending a connection from a calling station to a called station, bare wire terminals arranged in groups, said device having access to said terminals in common with a plurality of other devices, wipers mounted on a carrier movable in two straight line motions in different planes, a circular member rotatable in clock-wise and in anti-clock-wise direction, means for rotating said circular member clock-wise under directive control of a calling station for 30 moving said carrier in the first direction to position said wipers opposite a desired row of terminals, means for rotating said circular member clock-wise automatically for moving said carrier in the second direction to position said wipers upon certain terminals within said selected row, and means for automatically rotating said circular member anti-clock-wise to move said carrier into normal position.
16. In a signalling system, an automatic switching device for extending a connection from a calling station to a called station, bare wire terminals arranged in groups in vertical rows accessible to a plurality of said devices, wipers mounted on a carrier movable in two successive straight line motions, an electromagnet, means for first operating said electromagnet under directive control of a calling station and for then operating said 35 electromagnet automatically, means comprising a circular member rotatable progressively and continuously and controlled by said electromagnet when the same is under directive control for moving said carrier in a first direction to position said wipers opposite a certain row of terminals, and means including said circular member controlled by said electromagnet when the same is operated automatically for moving said carrier in a second direction to position said wipers upon terminals within said row.
17. In a signalling system, an automatic switching device for extending a connection from a calling station to a called station, said device having access to bare wire terminals arranged in groups in vertical rows, wipers mounted on a carrier movable in two directions in different planes, an electromagnet, means for first operating said electromagnet under directive control of a calling station and for then operating said electromagnet automatically, means comprising a circular member rotatable progressively and continuously and controlled by said electromagnet when the same is under directive control for moving said carrier in a first direction to position said wipers opposite a certain row of terminals, means controlled by said electromagnet when the same is operated automatically for moving said carrier in a second direction to position said wipers upon terminals within said row.
18. In a signalling system, an automatic switching device for extending connections between calling and called stations, said device having access to stationary bare wire terminals disposed in groups, wipers mounted on a carrier movable in straight line motions in a plurality of planes, an electromagnet, means for first operating said electromagnet under directive control of a calling station and for then operating said electromagnet automatically, means including a circular member rotatable progressively and continuously and controlled by said electromagnet when the same is under directive control for moving said carrier in a certain plane to position said wipers opposite a certain group of terminals, and means controlled by said electromagnet when the same is operated automatically for moving said carrier in another plane parallel to said group to position said wipers upon terminals within said group.
19. In a signalling system, an automatic switching device for extending connections between calling and called stations, said device having access to stationary bare wire terminals disposed in groups, wipers mounted on a carrier movable in successive straight line motions in a plurality of planes, an electromagnet, means for first operating

1. said electromagnet under directive control of a calling station and for then operating said electromagnet automatically, means including a progressively rotatable circular member controlled by said electromagnet when the same is under directive control for moving said carrier in a certain plane to position said wipers opposite a certain group of terminals, means controlled by said electromagnet when the same is operated automatically for moving said carrier in another plane but parallel to said group to position said wipers upon terminals within said group, and a separate electromagnetic means 15 for actuating said circular member to move said carrier into normal position.

2. In a signalling system, an automatic switching device for extending connections between calling and called stations, said device having access to stationary bare wire terminals disposed in groups, wipers mounted on a carrier movable in a plurality of planes, an electromagnet, means for first operating said electromagnet under directive control of a calling station and for then operating said electromagnet automatically, means including a progressively rotatable circular member directly controlled by said electromagnet when the same is under directive control for moving said carrier in a certain plane to position said wipers opposite a certain group of terminals, means including said circular member controlled by said electromagnet when the same is operated automatically for moving said carrier in another plane but parallel to said group to position said wipers upon terminals within said group, and a separate electromagnetic means for moving said carrier into normal position, all said movements of said carrier being executed in straight line motions.

3. In a signalling system, an automatic switch for extending connections between calling and called stations, said switch having access in common with a plurality of other switches to stationary bare wire terminals disposed in groups, wipers mounted on a carrier movable in a plurality of planes, an electromagnetically controlled driving means including a progressively rotatable circular member, means for initially actuating said means under directive control of a calling station and for then actuating the same automatically, means controlled by said driving means, when under directive control, for moving said carrier in a certain plane to position said wipers opposite a certain group of terminals, and means controlled by said driving means, when actuated automatically, for moving said carrier in another plane but parallel to said group to position said wipers upon terminals within said group, the movements of said carrier being executed in straight line motions.

4. In a telephone system, a plurality of switches, lines accessible to said switches and disposed in groups parallel to each other in a terminal field comprising bare wires suspended vertically, wipers in each of said switches, and a single driving means comprising a progressively rotatable circular member for moving said wipers in two successive motions to select a desired line.

5. In a telephone system, a plurality of switches, lines accessible to said switches and disposed in groups parallel to each other in a terminal field comprising bare wires suspended vertically, wipers in each of said switches, and a single driving means including a progressively rotatable circular member for moving said wipers in a plurality of successive motions in different planes, to select a desired line.

6. In a telephone system, a plurality of switches, lines accessible to said switches and disposed in groups parallel to each other in

- a terminal field comprising bare wires suspended vertically, wipers in each of said switches, a single driving means including a progressively rotatable circular member for moving said wipers in a plurality of straight line motions to select a desired line and a single driving means for moving said wipers to normal position.
27. In a telephone system, a plurality of switches, lines accessible to said switches and disposed in groups parallel to each other in a terminal field comprising bare wires suspended vertically, wipers in each of said switches, and a single driving means including a progressively rotatable circular member for moving said wipers in a plurality of straight line motions in different planes to select a desired line and for moving said wipers to normal position.
28. In a telephone system, a plurality of switches, lines accessible to said switches and disposed in groups parallel to each other in a terminal field comprising bare wires suspended vertically, each line comprising three wires, wipers in each of said switches, a progressively rotatable circular member, a single electromagnetic means for actuating said member to move said wipers successively in a plurality of straight line motions to select a desired line, and a single electromagnetic means for actuating said member to move said wipers to normal position.
29. In a telephone system, a plurality of switches, lines accessible to said switches and disposed in groups parallel to each other in a terminal field comprising bare wires suspended vertically, wipers in each of said switches, a rotatable circular member provided with a ratchet, means for rotating said member in a clock-wise direction to position said wipers upon a desired line, and means for rotating said member in reverse direction to move said wipers to normal position.
30. In a telephone system, a plurality of switches, lines accessible to said switches and disposed in groups parallel to each other in a terminal field comprising bare wires suspended vertically, each line comprising three wires, wipers in each of said switches, a rotatable circular member provided with a ratchet, means for rotating said member in a clock-wise direction to move said wipers in a plurality of successive straight line motions in different planes to position said wipers upon the terminals of a desired line, and means for rotating said member in reverse direction to move said wipers to normal position.
31. In a telephone system, a plurality of switches, lines accessible to said switches and disposed in groups parallel to each other in a terminal field comprising bare wires suspended vertically, wipers in each of said switches, a rotatable circular member provided with a ratchet, means for rotating said member to move said wipers in a plurality of successive straight line motions in different planes to select a desired line, and means for rotating said member to move said wipers into normal position.
32. In a switching apparatus, wipers mounted on a movable carrier and having access to stationary terminals, a pulley mechanism including a driving wheel and a supporting wheel, and a single electromagnetic means for actuating said pulley mechanism progressively in one direction to move said carrier in a plurality of successive motions in different planes to position said wipers on certain terminals.
33. In an automatic switching device, wipers mounted on a movable carrier and having access to stationary terminals, a pulley mechanism including a driving wheel provided with a ratchet, a single electromagnetic means for operating said pulley by means of said ratchet to move said carrier in a plurality of successive motions in different planes to position said wipers on desired terminals, and a single electromagnetic means for operating said pulley by means of said ratchet to move said carrier to normal position.
34. In a switching device, a plurality of wipers, terminals accessible to said wipers, a pulley mechanism, and a single electromagnetic means for actuating said mechanism to move said wipers in a plurality of successive motions to position said wipers on desired terminals.
35. In a switching device, wipers, terminals, a pulley mechanism, and a single electromagnetic means for operating said mechanism progressively in a single direction to move said wipers successively in a plurality of different directions to position the same upon desired terminals.
36. In a switching device, wipers, terminals, a pulley mechanism, a single electromagnetic means for actuating said mechanism progressively in one direction to move said wipers successively in a plurality of different planes to position the same upon certain of said terminals, and a separate electromagnetic means for actuating said mechanism in reverse direction to restore said wipers to normal position.

In witness whereof, I hereunto subscribe my name this 27th day of April, A. D. 1927.

JOHN WICKS.
